UNITED STATES PATENT OFFICE.

MATTHEW B. ADRIAN, OF MILWAUKEE, WISCONSIN.

X-RAY MACHINE.

Application filed January 22, 1923. Serial No. 614,074.

This invention relates to X-ray machines and is particularly directed to a machine for examining the foot. This application is a continuation in part of my co-pending application filed June 16, 1921, Serial No. 477,905.

The broad objects of this invention are, in general, the same as the objects specified in the co-pending application above referred to. Briefly stated, it is my broad object to provide an X-ray machine by which it is possible to examine the foot of a patient not only in an unloaded condition but also while the foot is active in sustaining its share of the weight of the patient's body.

Other objects which this invention has in common with those disclosed in my co-pending application are to provide an X-ray machine of a character particularly adapted to facilitate shoe fitting and orthopedic examination; to provide a machine of this character which is so constructed and arranged that it can readily be actuated by shoe salesmen and others who are not ordinarily skilled X-ray operatives; to provide a machine in which the patient can conveniently and naturally bring his weight to bear upon the foot under examination; to provide a machine in which the patient can conveniently examine his foot simultaneously with an examination by the attendant; to provide a machine with means enabling the attendant to use a pointer for the purpose of making criticisms intelligent to the patient; and to provide a machine having protective devices intended to secure the attendant and the patient against the inconvenience and harmful results which might, without such devices, ensue from the unskilled use of an X-ray machine.

The object, however, to which this application is particularly directed relates to the provision of an X-ray machine which will not only permit examination to be made of the foot in plan, but will also permit the foot of the patient to be viewed from either side in order that the articulation and position of the bones of the arch may be ascertained in connection with an examination of the bones of the forward portion of the foot.

More particularly stated, it is the object of the invention disclosed herein to provide

an X-ray machine in which a single X-ray tube may be adjusted to permit a side view as well as a plan view of the patient's foot. In the preferred embodiment of this invention, means is disclosed for enabling the patient to see a side elevation of the bony structure of his foot without altering his position in any respect. Other embodiments of this invention are so designed that by a slight change of position, the patient is enabled to obtain the new view of his foot. In either case, I have made it possible for a single X-ray tube and fluorescent screen to be used. Furthermore, this last mentioned design in which the patient changes his position slightly to inspect the bones of the arch in side elevation is particularly adapted for association with machines which have heretofore been constructed without provision for an inspection of the arch. It is possible by a slight modification of such existing machines to incorporate this additional feature to the mutual advantage of attendants and patients and with but slight additional expense.

The importance of this invention is enhanced in the eyes of those skilled in the art by reason of the fact that shoe fitting could be accomplished in a reasonably satisfactory way without the use of X-ray apparatus. This is particularly true of the fitting of the forward portions of the foot. The sense of touch of the patient and of the attendant can accomplish quite satisfactory results in the way of a proper fit of the forward portions of the foot. In cases, however, where treatment of the bones of the arch or even an examination of such bones is necessary, the work is particularly facilitated by a machine of the type which I have invented. Whereas it has heretofore been impossible for the average patient or the average shoe salesman to tell anything of the proper fit of a shoe at the arch or to discover with the slightest accuracy the position of the bones of the arch, it is now made possible for customer and salesman, or patient and doctor alike to examine the arch of the customer's or patient's foot and to determine at once whether or not the bones are properly articulated and positioned. As has heretofore been indicated, the fact that an examination of the arch can be conducted

with the same machine and at the same time as an examination of the forward part of the foot makes this invention of particular value.

5 Several embodiments of the invention are shown in the accompanying drawings, in which:

Fig. 1 is a side elevation of the forward portions of one type of machine embodying 10 this invention.

Fig. 2 is a front elevation of the same machine.

Fig. 3 is a section taken on line 3—3 of 15 Fig. 2.

Fig. 4 is a view corresponding to Fig. 1 illustrating a slightly modified form of invention.

Fig. 5 corresponds to Fig. 2 and is a front elevation of the device shown in Fig. 4.

20 Fig. 6 is a detail view on an enlarged scale showing a further slight modification in front elevation, with the front of the cabinet removed.

Fig. 7 is a detail taken on line 7—7 of 25 Fig. 6.

Fig. 8 is a plan view of a modified tube mounting adapted to be provided for machines now in use to enable such machines to embody the feature which forms the subject matter of this application.

Fig. 9 is a longitudinal vertical section through a machine cabinet showing the application of the mounting which is illustrated in Fig. 8.

35 Fig. 10 is a front elevation of an X-ray machine cabinet of simple construction utilizing the tube mounting shown in Figs. 8 and 9 and provided with an attachment enabling the side elevation of the patient's 40 foot to be viewed, portions of the front of the machine and attachments being broken away to expose the interior construction.

Fig. 11 is a section taken on line 11—11 of Fig. 8.

45 Fig. 12 is a detail front elevation of an indicating plate which is used in connection with the tube mounting shown in Figs. 8 to 11.

50 Like parts are identified by the same reference characters throughout the several views.

55 Although several modifications are illustrated in the accompanying drawings, it will be noted and will be more particularly brought out hereinafter that the modifications are in most part slight and are intended primarily to illustrate the fact that the various features disclosed herein may be combined in numerous ways to achieve 60 the objects which have heretofore been specified.

65 Each of the several embodiments herein disclosed includes a cabinet A. The lower portion of the cabinet comprises a boxlike structure 1 providing a platform 2 acces-

sible from the rear of the machine and adapted to support the weight of the patient. The box 1 normally houses an ordinary Coolidge X-ray tube, which is illustrated diagrammatically in Figs. 1 to 7, inclusive, as being disposed within a rectangular case 3. The box also preferably houses the entire mechanism necessary to the proper functioning of an X-ray tube including transformers, a rheostat, switches, etc. Such apparatus is well known in the art and has been fully disclosed in the co-pending application above referred to. Inasmuch as it forms no part of the present invention, it will not be further discussed herein.

Erected upon the forward end of the box-like device 1 is a superstructure or hood 4 which is preferably provided with an inclined rear wall 5 which is cut away centrally to an upright vertical panel 6 to provide a recess 7 for the limbs of the patient (see Fig. 7). Adjacent the platform 2, the panel 6 terminates in an inclined panel 8 which is so disposed as to intersect the plane of platform 2 at 9. A forward extension 10 of recess 7 is thereby provided to receive the foot or feet of the patient. Ordinarily, the extended recess 10 is made of sufficient size to receive one foot only, but this is not necessarily the case.

95 In the top panel 11 of hood 4, I provide one or more eye pieces permitting the patient or attendant, or both, to look into the interior of the hood for the purpose of viewing upon a suitable screen therein the foot 100 of the patient. The eye pieces 12 and 13 may be fixed and are intended primarily for the use of the attendant or other interested persons. The eye piece 14 is vertically adjustable in order that it may be made to 105 conform substantially to the height of the patient, thereby enabling him to view the image upon the screen without inconvenience. To this end, the eye piece 14 is preferably mounted at the upper end of a tube 110 15 which may be of elongated cross section as shown and is preferably adapted to telescope within a similarly formed collar 16 on the top panel 11 of hood 4. For the purpose of securing the device in any desired position of vertical adjustment, the rods 17 may be provided and the set screws 18 may be mounted in threaded relation to the eye piece support 19 and adapted to engage rods 17. The arrangement, as described more fully in my co-pending application, is such that when the set screws 18 are loosened, the eye piece 14, together with its carrying element 19 and the telescoping tube 15, may be raised and lowered relative to hood 4, to 120 accommodate the convenience of the patient. When the desired adjustment has been obtained, it may be fixed by again tightening the set screws 18.

125 It will be noted that the telescoping de- 130

vice which carries eye piece 14 is inclined forwardly at a slight angle and is also slightly offset forwardly of panel 6. The arrangement is such that an observer with 5 his foot in recess 10 will be caused to lean slightly forwardly in order to use eye piece 14 and will thereby be caused naturally to throw his weight upon the foot under observation.

10 As is well known in the art, the bodily member under X-ray investigation is not viewed directly. It is rather the image of said member upon a fluorescent screen rendered luminous by the action of the X-ray 15 that is seen by the patient and by the operator. In the device shown in Fig. 1, such a screen is disposed at 8', replacing the panel shown at 8 in the detail view in Fig. 7. With the X-ray tube in the position indicated at 20 3 in Fig. 1, the rays will emanate from said tube as indicated by the broken lines and will pass through the compartment 10, impinging upon the screen 8' which forms the 25 top of said compartment. The screen will thereupon become luminous in proportion to the intensity of the rays striking it and the varying resistance offered to the rays by the structure of the foot will produce upon the screen 8' an image of the foot showing the 30 bones in their exact relations to each other and to a shoe which may encase the foot at the time. The lines of sight from the eye pieces 12 and 14 are also indicated in broken lines in Fig. 1 illustrating how the patient and the 35 operator may view simultaneously the image on screen 8'. As will readily be understood, the bodily position of the patient may be shifted while the position of the bones is watched and from such observation the fitting of shoes and the making of other examinations of the foot is greatly expedited.

The means by which this same machine is rendered available for inspecting the bones of the arch will now be described. A rock 40 shaft 21 is journaled in the front upper portions of the box part 1 of the cabinet and terminates exteriorly of the cabinet in a manually operable crank 22. Within the cabinet, the rock shaft 21 supports the case 3 which houses the X-ray tube, thereby making it possible through the manipulation of 45 crank 22 to oscillate the X-ray tube about the axis of rock shaft 21. The arrangement is preferably such that the rock shaft may 50 be oscillated through 180° so that the case 3 housing the tube may be adjusted to the position in which it appears in Figs. 2 and 3 and to a position directly opposite. When 55 this is done, the tube will be at the height of the compartment 10 within which the foot of the patient is located and the rays emanating from the tube will pass horizontally and transversely through the foot of the patient. To receive an image of the foot, a 60 fluorescent screen is inserted alternatively in-

to either of the slots 23 which are shown in Fig. 2. A fluorescent screen inserted in one of said slots will be disposed vertically and will lie immediately adjacent the side of the patient's foot in a position to receive 70 the X-rays passing through said foot. It will be remembered, however, that such rays as pass through the foot with the tube in the position in which it is shown in Figs. 2 and 3 are travelling horizontally and in order to 75 render them visible to the patient and to the operator, it is necessary to provide a mirror such as is shown at 24. Each of the mirrors 24 is pivoted at 25 and each is preferably provided with a semi-elliptical spring 26 against which the case 3 can impinge without shock to oscillate the mirror about its axis at 25. The arrangement is such that in each instance, the case 3, upon being elevated to the horizontal as shown in Fig. 2, 80 will impinge upon one of the springs 26 beneath a mirror 24 and will elevate said mirror out of the way as is indicated in dotted lines at the right of Fig. 2. Screws 27 provide adjustable stops for limiting the downward movement of each mirror.

With the parts as shown in Fig. 2, it will be obvious that a patient looking into the eye cup 14 or an operator looking into eye cup 13 will be able to see in the left hand mirror 24 light emanating from the radiant screen inserted in slot 23 and thus to view the image of the patient's foot in side elevation. When the inspection is completed, the crank 22 may be utilized to swing case 100 3 downwardly to its normal position as indicated in Fig. 1, whereupon mirror 24 will be allowed to return by gravity and to contact with screw 27 so that should it now be desired to inspect the patient's foot from an 105 opposite viewpoint, the fluorescent screen can be inserted into the righthand slot 23 and the mirror 24 will be properly set to receive the light from said screen and reflect such light upwardly to eye pieces 12 and 14. 110

The position of the patient's foot is indicated in broken lines 30 in Fig. 3 and the fluorescent screen 31 is shown to be properly positioned in the lefthand slot 23 to be acted upon by X-rays emanating from case 3 and 115 passing through the patient's foot.

It is particularly to be noted that the portions 32 of hood 4 which lie at either side of the recess 7 in which the patient's leg is disposed provide space for the case 3 when said case is swung upwardly to the position in which it appears in Figs. 2 and 3. Where 120 it is desired to view the arch of the patient's foot, it is essential that the X-ray tube be disposed at a sufficient distance rearwardly from the front of the machine to include at least such portions of the foot as lie within the cone of rays emanating from the tube in the manner designated in Fig. 3. It is desirable, therefore, to have the side portions 125 130

of the hood extend rearwardly as at 32 so that the case 3 which houses the Coolidge tube may move freely in the plane in which it appears in the accompanying drawings.

5 In the embodiment which has just been discussed, it is necessary for the operator not only to shift position of the Coolidge tube contained in case 3 but also by means of a separate and distinct operation to position in one of the slots 23 a suitable fluorescent screen such as is designated at 31. It may be well at this time to disclose briefly the assembly of such a screen in order that the manner in which it is inserted and withdrawn from the slideways provided therefor may be more fully understood.

A fluorescent screen is shown in detail in Figs. 9 and 10 and is designated in its entirety by the reference character 31. The 20 screen preferably includes a frame 33 within which are bound in successive strata a sheet of bakelite or other substance opaque to ordinary light, designated at 34, the fluorescent screen proper which is shown at 35, and a 25 sheet of lead glass which appears at 36. The opaque substance represented at 34 has the function of cutting off light rays emanating from the Coolidge tube which is preferably used in connection with a machine of this 30 sort. This opaque substance permits X-rays to pass freely to the sensitive fluorescent screen 35, which is afforded physical protection against breakage or scratching by the presence of the bakelite sheet 34. As has 35 previously been explained, the X-rays which reach the fluorescent screen 35 cause said screen to become luminous and the illumination thereof is visible to the observer through the lead glass plate 36. Lead glass is used 40 because it has the peculiar property of obstructing and preventing the passage of the X-rays while permitting ordinary light to pass freely through it. The glass also serves to protect the delicate fluorescent screen 35. 45 This arrangement of the three-ply screen described above is familiar to those skilled in the art and the only point which it is desired to bring out particularly is the fact that the assembled screen is preferably mounted in a 50 channeled frame 33, as shown in Fig. 9, and is thereby adapted to be handled freely and to be moved in and out of the suitable guideways provided for the frame as occasion demands.

55 In order to obviate the necessity for manually changing the position of screen 31 by an operation separate from that required to shift the position of the case 3 which contains the Coolidge tube, the embodiment of 60 this invention disclosed in Figs. 4 to 7, inclusive, has been devised. This construction differs from that shown in the first three figures of the drawings principally by reason of the fact that the bracket 37 which 65 supports case 3 from rock shaft 21 is ex-

tended upwardly beyond said rock shaft in the manner indicated at 38 and carries screen 31 in a position adapted to receive the emanations from case 3 in the manner shown. With the embodiments shown in Figs. 4 and 5, it is only necessary to utilize crank 22 to oscillate the rock shaft 21 to any one of its three positions, which lie within 180° of movement. When the case 3 which contains the Coolidge tube is elevated to the position 75 in which it appears in dotted lines in Fig. 5, the screen 31, being connected therewith, will move simultaneously from the full line position in Fig. 5 to its dotted line position in said figure and will, regardless of the 80 position of case 3, at all times be maintained directly opposite the case and in the proper place to receive X-rays emanating from case 3 and passing through the foot of the patient. The means employed for lifting mirrors 85 24 out of the way to permit the proper positioning of case 3 may be the same as that heretofore disclosed. In other words, it may include semi-elliptical springs 26 disposed beneath each mirror and adapted to 90 receive the impact of the case 3 as it assumes its elevated position.

If desired, however, shock to the apparatus may be lessened by directly connecting each mirror with the oscillating bracket 37 95 in the manner indicated in Figs. 6 and 7. The mirrors 24 are mounted in the manner previously disclosed with the exception that the pintles 25 upon which the mirrors are pivoted are extended and provided with 100 short lever arms 39 to which a cord 40 is secured. The cord 40 passes over pulleys 41 journaled on the front panel of the machine and extends downward intermediate its ends to engagement at 40' with a portion of 105 bracket 37 at a point somewhat removed from the axis upon which said bracket oscillates. The arrangement is such that when the bracket 37 is swung through its arc of movement, the mirrors 24 will be correspondingly actuated so that one of said mirrors will be automatically removed from the path 110 of case 3 when said case is swung to the position in which it appears in dotted lines in Fig. 6 or to a position 180° removed from 115 the position in which it is shown. When one of the mirrors 24 is elevated as shown in Fig. 6, the other will always be properly positioned by means of one of the screws 27 which has previously been described or by 120 some other suitable form of stop for limiting the downward movement of said mirrors.

If desired, means may be provided for cushioning the movement of bracket 37 and its associated tube-containing case 3 and 125 fluorescent screen 31 into any of its predetermined positions. This may conveniently be done pneumatically by providing a cylinder 42 pivotally supported from a pin 43 carried by the front panel of box 1. A pis- 130

ton 44 reciprocable within the cylinder is associated through rod 45 with the bracket 37, to which the rod may conveniently be pivotally connected at 46. A spring 47 seated between the piston 44 and the head of cylinder 42 may be utilized, if desired, to partially counterbalance the weight of the case 3. This is desirable when the weight of case 3 and the Coolidge tube therein greatly exceed 10 in moment about rock shaft 21 the screen assembly 31.

Fig. 7 adds considerably to the disclosure already discussed herein, since the embodiment of this invention shown in Fig. 7 provides means for moving the Coolidge tube and fluorescent screen longitudinally of the machine so that in their vertical position they may be aligned with the forward portions of the foot and in their horizontal position they may be moved rearwardly into alignment with the arch portions of the foot.

It will be remembered that the recess 7 which accommodates the leg of the patient is bounded at its forward side by an upright 25 panel 6. From the recess 7, the foot of the patient extends still further forward in the extended recess 10 therefor provided. If it were not for the vertical panel 6 an elongated fluorescent screen 31 might be provided 30 which would cover the entire length of the patient's foot. It is desirable, however, to have the patient stand erect or lean slightly forwardly in order to bring his weight upon the ball of his foot. Therefore, the panel 6 35 represents the extreme rearmost limit to which the screen 31 can be moved when the tube and screen are vertically disposed for the purpose of viewing the patient's foot in plan. It will be obvious that with the tube 50 40 and screen 31 in the position indicated in Fig. 7 and with the patient's foot in the position indicated therein in dotted lines, the forward portions of the foot will be fully delineated upon the screen so that the image of these 45 portions will be clearly visible through the eye cups in the top of the hood portion 4 of the cabinet. It will also be obvious, however, that the path of the X-rays between tube 50 and screen 31 will not include to any 50 considerable extent the arch of the patient's foot when tube and screen are swung to the position in which they are illustrated in Fig. 5. It will be remembered, however, that the portions 32 of the hood which lie upon either side of recess 7 are extended rearwardly and provide ample room to accommodate the casing 3 which houses the tube, as well as the screen. Accordingly, I provide for moving both the screen and casing 3 rearwardly at such times as it is desired to inspect the arch.

For this purpose, I extend the rock shaft 21 in the manner indicated in Fig. 7 and I provide as a bearing for the extended shaft 65 an elongated sleeve 51 which may be pro-

vided with a flange 52 enabling it to be secured to the front of the cabinet. An axially disposed slot 53 extending diametrically through said sleeve and opening to the end thereof is adapted to receive a cross pin 54 70 set in the rock shaft 21. The arrangement is such that with the rock shaft 21 and bracket 37 carrying the screen and tube in the position in which they appear in Fig. 7, the pin 54 will contact with the outer extremity of sleeve 51, thereby maintaining the screen and tube in the forward position in which they are illustrated in full lines. If, however, the rock shaft 21 be rotated by manipulation of handle 22 in either direction, the pin 54 will register with and will be received into slot 53 in sleeve 51, thereby enabling the attendant to move rock shaft 21 axially and thus to shift screen 31 and tube 50 bodily to the rear, where the screen will then occupy the position in which it is shown in dotted lines. A dotted line showing of the casing 3 is omitted from Fig. 7 to avoid complicating the drawing. A spring 55 confined between the front panel of the cabinet and the bracket 37 serves to facilitate the rearward movement of bracket, screen and tube when the pin 54 of rock shaft 21 registers with the slot 53 as aforesaid. It will be obvious that by this arrangement a single hand lever may be utilized to bring the tube and screen into the best possible positions for the examination of the arch as well as of the forward portions of the foot.

It must be clear that in their rearward positions the casing 3 and screen 31 will be received into the rearwardly extended portions 32 of the hood upon either side of recess 7. The interaction of pin 54 with slot 53 prevents bracket 37 from being rotated at this time from its horizontal position toward the vertical position in which it appears in Fig. 7 and thereby prevents injury to the screen which would certainly occur if the bracket could be rotated to bring the screen into contact with the side margins of the vertical panel 6. The provision of slot and pin ensures that the bracket 37 must first be pulled forwardly before it can be rotated and the pin does not leave the slot until the bracket is sufficiently advanced in its position so that the screen will clear panel 6 in the manner illustrated.

Each of the machines which has been discussed herein has been built with the express purpose in mind of providing a tube adjustable to permit the arch as well as the forward portions of the patient's foot to be viewed without any change of position on the part of the patient. It is possible, however, to provide an even simpler mounting for the X-ray tube, while providing for an inspection of the patient's arch as well as of the forward portions of his foot. Such a device is shown in Figs. 8 to 12, inclusive.

It is necessary that the patient's foot occupy a slightly different position during the examination of the forward portion thereof than during the examination of the arch portions. This slight inconvenience, however, is offset by the fact that this modified embodiment of my invention is such that many machines now in use and adapted only for inspections of the forward portions of the foot can readily be converted to permit the making of the very much more important examination of the patient's arch. As a disclosure of this new embodiment of my invention proceeds, it will be apparent that not only is a single X-ray tube used to accomplish this added function, but also a single screen framed in the manner already described may be shifted from place to place as desired to bring it into proper alignment with the tube and the patient's foot and thereby to permit the proposed inspection.

In the embodiment shown in Figs. 8 to 12, inclusive, the cabinet 1 and the hood portion 4 thereof are essentially similar to the corresponding parts already described. The chief difference consists in the fact that the cabinet may be made much narrower because with this design, it is not necessary to have the X-ray tube swing about the axis of rock shaft 21 in the manner already described. A further modification consists in replacing the inclined panel 8 which, in Fig. 7, lies directly above the patient's foot with a removable fluorescent screen panel 31 which is enclosed in a frame 33 in the manner already described. In order to make the screen 31 removable, the vertical panels 55 and 56 which comprise the sides of recess 7 are provided with inclined grooves 57 constituting a slideway enabling the framed fluorescent screen to be slid inwardly immediately beneath the vertical panel 6. The floor 2 may be extended as at 2' to shut off from the hood all light which may be produced by the Coolidge tube 50 in the lower part of the cabinet. An aluminum sheet 59 may be used to filter the X-rays and protect the patient from possible burns.

In order that the tube mounting may be made clear, the preferred construction of the tube will first be described.

The X-ray tube preferably includes not only the ordinary Coolidge tube 50 but also a protecting cover 60 of lead glass which is shaped to conform to the tube and is provided intermediate its ends with lenses 61 apertured to receive bolts 62 by means of which its two parts may be clamped together about the usual bulbous portion of tube 50. The lead glass serves to confine the X-rays which are permitted egress only through an aperture 63. It will be obvious, therefore, that by rotating both tube 50 and

its enclosing glass shield 60, the X-rays may be directed as desired.

To permit such rotation, the posts 64 and 65 are positioned centrally in the cabinet 1 and are provided at their upper extremities with removable yokes 66 adapted, when in place upon said posts, to provide journals in which the cylindrical extremities of the lead glass shield 60 can rotate. The posts 64 and 65 as well as yokes 66 are preferably constructed of some insulating material such as fiber.

To enable the tube to be rotated in its bearings by an operator on the exterior of the cabinet, I provide a clamping device 67 which is preferably rectangular in form and open at its center to permit the electrical lead 68 to reach the end of the Coolidge tube 50. A yoke 69 is associated with the rectangular frame element 67 and may be clamped thereto by bolts 70. The operating rod 71 has a threaded extremity upon which a nut 72 is engaged for the purpose of clamping a central portion of member 67 between said nut and the collar 73 which may be integrally formed upon said rod. The rod extends outwardly through the front panel of cabinet 1 and is provided exterior thereto with an operating knob or handle 74 from which projects radially a finger 75. Suitable stop pins 76 on the front wall of the cabinet designate extreme positions to which handle 74 may be rotated. The finger 75, being disposed in the same direction as that in which the X-rays emerge from opening 63 serve also as a pointer to indicate to the operator the position of the parts within the cabinet. This position may be defined by characters upon the exterior of the cabinet in the manner illustrated in Fig. 12.

It will be obvious from the foregoing description that the operator is provided with means at the front of the cabinet by which he can readily rotate the entire X-ray tube assembly to cause the emanations therefrom to pass straight upwardly or to either side. When the X-rays are directed upwardly and screen 31 is in the position in which it appears in Fig. 9, it will be clear that the patient's foot in recess 10, or rather the image thereof, will be clearly visible upon the screen. When, however, it is desired to inspect the arch of the patient's foot, the tube will be manipulated by means of handle 74 into either of the two positions designated by L and R in Fig. 12. Fig. 10 shows the tube in the position which it assumes when the handle in turn brings finger 75 to the position designated by R in Fig. 12.

In order to support the patient's foot in the path of the X-rays emanated from tube 50 when said tube is in the position in which

105

110

115

120

125

it is illustrated in Fig. 10, I provide a step 78 at one side of the cabinet. It is necessary, therefore, for a patient who has had the forward portions of his foot examined 5 to descend from the platform 2 to the step 78 for the purpose of having the arch portions of his foot examined.

Step 78 may form a part of the cabinet itself or, as illustrated in Fig. 10, it may be 10 supported by rods 79 from a subordinate cabinet 80 which constitutes an attachment for the main machine. The cabinet 80 is provided with a vertically disposed guideway between members 81 and 82 into which 15 the fluorescent screen 31 is adapted to be slid from the front. It will be understood that the screen will be withdrawn from grooves 57 at the completion of the examination of the forward portions of the 20 patient's foot and will be inserted between members 81 and 82 when an examination of the arch portions is desired. The secondary cabinet 80 contains a mirror 83 disposed at an angle of 45° and adapted to reflect upwardly rays of light emanating from the 25 fluorescent screen. A hood 84 corresponding in general to the hood 4 of the main cabinet is provided at its upper extremity with an eye piece 85 through which the 30 operator or patient may look to inspect in the mirror 83 the reflection of the image upon the fluorescent screen.

It will be understood that the attachment comprising the auxiliary cabinet 80 and the 35 step 78 may be moved bodily around the main cabinet 1 and may be positioned upon the other side thereof in a location corresponding to that in which it appears in Fig. 10. The lead cones 86 may be used, if 40 desired, to confine the X-rays to a path which includes the area of the fluorescent screen assembly 31. The confinement of the X-rays is desirable in order to prevent possible burns or other injuries to patients or 45 bystanders. It will likewise be understood that aluminum plates 87 may be disposed at any point in the path of the X-rays to serve as a filter and remove those portions of the rays which tend to cause burns. Such a 50 plate is shown at 87 on the right hand side of the cabinet as viewed in Fig. 10. It will be understood, however, that these plates will be used wherever necessary in any of the apparatus disclosed in this application.

55 It will be obvious from the foregoing description of the device shown in Figs. 8 to 12, inclusive, that it permits of the making of a suitable examination of the arch of a patient's foot as well as of the forward portions thereof and that such an examination can be made with almost as great facility as is the device disclosed on Sheet 1 of the drawings. It will also be obvious that in order to use for examinations of the arch a 60 machine which was constructed only to per-

mit examinations of the forward portions of the foot, it is only necessary to provide a mounting for the X-ray tube enabling it to be rotated in a manner herein disclosed and to add to the main cabinet an auxiliary 70 device provided with a step and with a fluorescent screen such as is shown at 80. The mirror in the auxiliary cabinet shown at 80 is obviously unessential and is intended merely to promote the convenience with 75 which the device may be used.

It will be noted that the disclosure herein completely satisfies the objects specified for this invention. In each of these machines, an examination of the arch portions 80 of the patient's foot is possible by means of the same general arrangement which permits an examination of the forward portions of the foot to be made. In each case, the adjustment of the tube proper is accomplished simply by the rotation of the tube upon its axis. In the structure shown in Figs. 1 to 7, inclusive, the tube is rotated about an axis remote from itself in order to permit both of the examinations above referred to to be made without requiring the patient to shift the location of his foot. It will be observed, however, that even though the axis about which the tube moves is remote from the axis of the tube, the ultimate result accomplished includes a rotation of the tube upon its own axis so that the rays which in the original position of the tube were upwardly directed are, at the conclusion 90 of tube movement, directed horizontally to one side or the other.

I recognize that under many circumstances it is desirable not only to view an image of the bones of a patient's foot but also to make a record of their arrangement and respective location. For this purpose, the frame 33 which constitutes a part of the fluorescent screen assembly may be provided on its under side with a pair of oppositely disposed flanged elements 90 of such a character as to be adapted to provide a slide-way for the mounting of a photographic plate 91. Such a plate, together with the flange members 90, is shown in Fig. 9 and it will be understood that anyone of the fluorescent screen assemblies shown at 31 in the accompanying drawings may be equipped with similar flanged members to receive a photographic plate, if desired.

110 In using a photographic plate in a device of this kind, it is customary to insert the sensitive plate in an envelope of some material which is opaque to ordinary light but is transparent to X-rays. The plate encased within its protecting envelope is so disposed with reference to the screen assembly 31 that the X-rays will pass through the plate before they reach the fluorescent screen. Thus the operator or patient looking at the screen 115 will see thereon the same image which is be- 120

125 130

ing made permanent upon the sensitive photographic plate.

The alternative use of the fluorescent screen and a photographic plate in connection with X-ray work is well known in the art, and this discussion of the particular mounting of screen and plate has been appended solely for the purpose of making it clear that when the term "plate sensitive to X-ray" is used in the accompanying claims, it is intended to refer both to the photographic plate upon which a permanent image is produced and to the fluorescent screen upon which a temporary image is produced.

15 By reason of the full and complete disclosure herein, those skilled in the art will be able to combine the various refinements herein disclosed to produce many different arrangements of parts to obtain similar results. I do not, therefore, wish to be limited to the specific embodiments herein disclosed, but claim my invention as follows.

I claim:

20 1. In a device of the character described, the combination with a cabinet, of an X-ray tube housed therein and mounted for rotative adjustment, whereby to be adjustable to emanate rays in a plurality of directions, and motion transmitting connections for the 25 rotative adjustment of said tube and including a manually operable portion exterior of said cabinet, said cabinet providing supporting means adapted to carry the weight of a patient's foot in operative relation to said tube in the several positions thereof, whereby said foot may be viewed by rays passing vertically or laterally therethrough and emanating from a single tube within said cabinet.

40 2. An X-ray apparatus for examining a foot under the normal weight of the body of a patient, including means for supporting the patient with body weight upon the foot, means for adjusting and mechanically supporting an X-ray tube underneath the foot and at the sides thereof at predetermined distances therefrom, and means for directing the rays of said tube through the foot from any one of said positions of adjustment.

45 3. In an X-ray machine designed to facilitate the examinations of the human foot, the combination with a foot support adapted to allow the patient to stand and apply the weight of his body to the foot to any desired degree and an adjustable mounting for an X-ray tube movable to various positions underneath and at the sides of a foot on said support, an X-ray tube carried by said mounting and supported to deliver its rays 50 through said foot from any of said positions of adjustment, and means sensitive to X-rays correspondingly adjustable and simultaneously with said tube on the other side of said foot to receive the rays passing through the foot.

4. An X-ray machine including means for supporting a foot under load, an X-ray tube rotatably mounted to project its rays vertically or laterally through a foot supported by said means, and a fluorescent screen 70 movable simultaneously with said tube for adjustment to receive the vertically or the laterally projected rays subsequent to their passage through said foot.

5. An X-ray machine including a cabinet 75 providing means for supporting a patient's foot under the weight of a patient's body, an X-ray tube rotatably mounted within said cabinet and provided with means exterior to said cabinet for its manual adjustment, and a fluorescent screen adjustable to receive rays emanating from said tube in one position thereof.

6. In an X-ray machine, the combination 80 with an X-ray tube, of means for supporting the foot of a patient under varying conditions of load, and means for directing the emanations from said tube through the foot from positions at the bottom and sides thereof, and means for receiving the image produced by said rays from any direction in which they may be derived from said tube.

7. In an X-ray machine for examination of the foot of a patient, the combination 85 with an X-ray tube, of a mounting for the tube adapted to permit rotative adjustments of the tube to direct the emanations at different angles, and means for supporting the foot of a patient under load and in positions 90 to receive said emanations from the bottom or side at predetermined distances from the tube.

8. An X-ray machine including a cabinet 95 providing means for supporting a patient's foot under load, a tube rotatable within said cabinet and adjustable by its rotation to project its rays vertically or laterally through a foot so supported, a screen sensitive to X-rays positioned to receive rays laterally 100 projected through said foot, and a mirror inclined at an angle rendering the image on said screen visible from above.

9. An X-ray machine including a cabinet 105 providing means for supporting a patient in a standing position with the foot to be examined subject to his weight in any desired degree, a hood above said means provided with an eye piece, an X-ray tube rotatably adjustable within said cabinet to project its rays at a plurality of angles through a foot 110 supported by said means, a screen sensitive to X-rays and adapted to receive rays passing through said foot at an angle from the vertical, and a mirror inclined to permit the 115 illumination of said screen to be reflected to an observer at a height greater than said screen.

10. An X-ray machine including a cabinet 120 providing a platform adapted to support a 125

- patient's foot, in a position to receive the weight of the patient in varying degrees during an examination of the foot, a hood rising above said platform and provided with a recess partially receiving a patient's foot, an X-ray tube adjustable within said cabinet to project X-rays laterally obliquely and vertically through a foot in said recess, and a fluorescent screen adjustable to receive rays emanating from said tube through said foot in any of the positions of adjustment of said tube, means exterior to said cabinet for manually adjusting said tube and screen, and a mirror adapted in one position of said screen to reflect toward the top of said hood light radiating therefrom. 70
15. An X-ray machine providing a platform adapted to support a patient's foot under load and including a hood partially enclosing a portion of said platform, an X-ray tube within said cabinet, a bracket adjustably supporting said tube for rotation about a foot supported upon the partially enclosed portion of said platform as a center, a 80 fluorescent screen carried by said bracket diametrically opposite from said tube and adapted regardless of the position of said tube to receive emanations passing through a foot so supported, and a pair of mirrors 85 upon opposite sides of said cabinet inclined to reflect upwardly light rays radiating from said screen in opposite positions thereof. 10
16. An X-ray machine including a cabinet provided with a platform and including a hood partially enclosing a portion thereof, said portion being adapted to support a patient's foot under load, an X-ray tube, a fluorescent screen, a bracket providing a mounting for said tube and screen, 95 upon opposite sides of the partially enclosed portion of said platform, means for rotating said bracket about a pivot point intermediate said tube and screen, a mirror pivoted to the side of said cabinet and adapted in one position of said tube and screen to receive and reflect upwardly light radiating from said screen, and means rendering said mirror automatically adjustable about its pivot to provide room for one of the members carried by said brackets in one 100 adjustment of said bracket. 105
17. In an X-ray machine for examining a foot under load, the combination with a cabinet providing a platform adapted to support a loaded foot and an eye piece above said platform, of a bracket rotatable about an axis intersecting the position of a foot upon said platform, an X-ray tube supported from said bracket and movable therewith to a plurality of positions about said foot, a fluorescent screen adjustable to positions upon opposite sides of said foot to receive rays from said tube modified by passage through said foot, and a pair of mirrors 110 pivoted to said cabinet and normally positioned at an angle adapted to reflect upwardly toward said eye piece, rays of light radiating from said screen, each of said mirrors being automatically movable from the path of said tube as said tube approaches 115 an elevation corresponding to that of a foot upon the platform. 120
18. An X-ray machine including the combination with a cabinet providing a plat- 125
10. An X-ray machine including a cabinet providing a platform adapted to support a foot under load, a hood rising above said platform and partially enclosing a portion thereof, an eye piece in said hood above said platform, an X-ray tube adjustable within said cabinet to project rays at a plurality of angles through a foot supported upon the partially enclosed portion of the platform, a fluorescent screen adjustable to receive rays emanating from said tube subsequent to their passage through said foot and regardless of their angle of projection, and a mirror adapted in one position of adjustment of said screen to reflect an image thereon to said eye piece. 130
11. An X-ray machine including a cabinet providing a platform adapted to support a foot under load, a hood rising above said platform and partially enclosing a portion thereof, an X-ray tube adjustable within said cabinet to project rays vertically and laterally through a foot so supported, means exterior to said cabinet for manually adjusting the position of said tube, and a fluorescent screen adjustable to receive rays projected in either of said directions. 140
12. An X-ray machine including a cabinet providing a platform adapted to support a foot under load, a hood rising above said platform and partially enclosing a portion thereof, an eye piece in said hood above said platform, an X-ray tube adjustable within said cabinet to project rays at a plurality of angles through a foot supported upon the partially enclosed portion of the platform, a fluorescent screen adjustable to receive rays emanating from said tube subsequent to their passage through said foot and regardless of their angle of projection, and a mirror adapted in one position of adjustment of said screen to reflect an image thereon to said eye piece. 150
13. An X-ray machine including a cabinet providing a platform adapted to support a patient's foot under load, a hood partially enclosing a portion of said platform and provided with an eye piece above the level thereof, an X-ray tube adjustable within said cabinet to project rays vertically and laterally through a foot upon the partially enclosed portion of said platform, a fluorescent screen adjustable to receive said rays in a plurality of positions of adjustment of said tube, and a plurality of mirrors adapted in different positions of said screen to reflect images thereon toward said eye piece. 160
14. An X-ray machine including a cabinet providing a platform for the support of a patient's foot under load and including a hood partially enclosing a portion of said platform, an X-ray tube provided with a supporting bracket adjustable about an axis including a foot supported upon the portion of said platform so enclosed, said tube and bracket being adjustable to project the rays of said tube laterally and vertically through said foot, a screen movable in conformity with said tube and disposed diametrically opposite to said tube, across said foot to re-

- form adapted to support a foot under load, of a bracket within said cabinet pivoted for movement about an axis intersecting the position of a foot upon said platform, an 5 X-ray tube supported from said bracket and movable therewith to various positions about said foot, a fluorescent screen adapted in one position of said tube to receive X-rays therefrom subsequent to the passage of said 10 rays through a foot upon said platform, a mirror pivoted to said cabinet and normally disposed at an angle to said screen adapted to reflect light emanating therefrom in a transverse direction, and motion transmitting 15 connections enabling said mirror to be actuated about its pivot by the movement of said tube and bracket into a given position other than the position aforesaid.
19. In an X-ray machine the combination 20 with a cabinet providing a platform adapted to support the weight of a foot under load, of a bracket pivoted within said cabinet for movement about an axis intersecting the position of a foot upon said platform, an X-ray tube supported from said 25 bracket and movable therewith from positions upon either side of said foot to a location immediately therebeneath, means adjustable to receive in a plurality of positions 30 of said tube rays emanating therefrom and passing through said foot, said means being sensitive to rays emanating from said tube, a plurality of mirrors pivoted within said cabinet, and an adjustable stop associated 35 with each of said mirrors to limit the pivotal movement thereof in one direction whereby each mirror is positioned to render said sensitive means visible from above.
20. In an X-ray machine the combination 40 with a cabinet providing a platform adapted to support the weight of a foot under load, of a bracket pivoted within said cabinet for movement about an axis intersecting the position of a foot upon said platform, an X-ray tube supported from said bracket and movable therewith from positions upon 45 either side of said foot to a location immediately therebeneath, means adjustable to receive in a plurality of positions of said tube rays emanating therefrom and passing through said foot, said means being sensitive to rays emanating from said tube, a plurality of mirrors pivoted within said cabinet, an adjustable stop associated with 50 each of said mirrors to limit the pivotal movement thereof in one direction whereby each mirror is positioned to render said sensitive means visible from above, and motion transmitting means associated with each of 55 said mirrors and adapted to be actuated by the ultimate movement of said tube to either of its positions at the side of said foot, whereby each mirror may be elevated about its pivot point from the path of said tube.
- 60 21. In an X-ray machine, the combination 65 with a platform adapted to support a foot under load, of a structure partially enclosing a portion of said platform, an X-ray tube within said structure and operable in a position at the side of a foot upon said 70 platform, a sensitive screen adapted to receive rays emanating from said tube and passing horizontally through said foot and adapted to be rendered radiant by the action of said rays, and a mirror inclined to render 75 said radiant screen visible from above.
22. In an X-ray machine, the combination with a platform adapted to support a foot under load, of a structure partially enclosing a portion of said platform, an X-ray 80 tube within said structure and operable in the position at the side of a foot upon said platform, a sensitive screen adapted to receive rays emanating from said tube and passing horizontally through said foot and 85 adapted to be rendered radiant by the action of said rays, and a mirror inclined to render said radiant screen visible from above, and means for adjusting the angle of inclination of said mirror.
- 90 23. An X-ray machine including the combination with a platform adapted to support a patient's foot under load, of a structure partially enclosing a portion of said platform, an X-ray tube, a screen sensitive to rays emanating from said tube, and a pivotally mounted bracket supporting said tube and screen upon opposite sides of the portion of said platform so enclosed, said bracket being adjustable to revolve said tube and screen as a unit about a foot positioned upon said portion of the platform.
- 95 24. An X-ray machine including the combination with a platform adapted to support a patient's foot under load, of a structure partially enclosing a portion of said platform, an X-ray tube, a screen sensitive to rays emanating from said tube, and a pivotally mounted bracket supporting said tube and screen upon opposite sides of the portion of said platform so enclosed, said bracket being adjustable to revolve said tube and screen as a unit about a foot positioned 100 upon said portion of the platform, and means for moving said bracket, tube and screen axially into alignment with different portions of said foot.
- 105 25. An X-ray machine including a cabinet providing a platform adapted to support a patient's foot under load, a structure partially enclosing a portion of said platform and adapted partially to enclose a foot thereon, an X-ray tube and a fluorescent screen mounted oppositely with respect to said foot and for revolution as a unit about an axis intersecting said foot, and means exterior to said cabinet for revolvably adjusting said tube and screen.
- 110 26. An X-ray machine including a cabinet providing a platform adapted to sup-

port a patient's foot under load, a structure partially enclosing a portion of said platform and adapted partially to enclose a foot thereon, an X-ray tube and a fluorescent screen mounted oppositely with respect to said foot and for revolution as a unit about an axis intersecting said foot, and means exterior to said cabinet for revolubly adjusting said tube and screen, means enabling said tube and screen to be adjusted parallel to the axis about which they are revoluble.

27. An X-ray machine including a cabinet providing a platform adapted to support the weight of a foot under load and providing a structure adapted partially to enclose a foot so supported, a shaft extending into said cabinet substantially at the level of a foot so supported, a bracket carried by said shaft within the car beneath an X-ray tube, and a fluorescent screen carried by said bracket and disposed oppositely with reference to a foot so supported, and a handle upon said shaft exterior to said cabinet enabling said shaft, bracket, screen and tube to be revolved as a unit about the axis of said shaft and to be moved bodily parallel to said axis.

28. An X-ray machine including a cabinet providing a platform adapted to support a foot under load, a portion of said platform being partially enclosed, a bracket within said cabinet, an X-ray tube supported therefrom, a fluorescent screen supported therefrom upon an opposite side from said tube with the foot of the patient interposed between it and said tube, a mounting for said bracket enabling it to be oscillated about an axis substantially at the level of said platform, and interacting elements respectively revoluble with said bracket and stationary with respect thereto, said elements being adapted in one position of revolution of said bracket to permit bodily axial movement thereof and in other positions of said bracket to oppose such movement.

29. An X-ray machine including a cabinet having a foot supporting platform and a hood having rearwardly extending portions at either side of the normal position of said foot upon said platform, an X-ray tube, a fluorescent screen, a bracket supporting said tube and screen oppositely with reference to a foot upon said platform and pivotally mounted whereby said tube and screen may be revolved as a unit about a foot so supported, a shaft provided with a transverse pin, a sleeve provided with an axially extending slot adapted to receive said pin, said bracket being mounted upon said shaft and the disposition of said slot being such as to permit said shaft and bracket to move axially rearwardly when the tube and screen carried by said bracket are aligned with the rearwardly extending portions of said hood.

30. An X-ray machine including a cabi-

net providing a platform adapted to support a patient's foot under load, said cabinet having rearwardly extending portions upon each side of a foot so supported, an X-ray tube and fluorescent screen, a bracket supporting said tube and screen for movement as a unit within said cabinet, means exterior to said cabinet for moving said bracket revolubly and axially, and means for obstructing the axial rearward movement of said bracket at such times as said tube and screen are not aligned with the rearwardly extending portion of said cabinet.

31. An X-ray machine including a cabinet providing a platform adapted to support a patient's foot under load, said cabinet being provided with rearwardly extending portions adapted partially to enclose a foot so supported, an X-ray tube revoluble within said cabinet about an axis longitudinally intersecting a foot so supported, a screen revoluble about said foot oppositely to said tube, and means for adjusting said screen parallel to said axis whereby rays traversing different portions of said foot may be received thereby.

32. An X-ray machine including a cabinet providing a platform adapted to support a patient's foot under load, said cabinet being provided with rearwardly extending portions adapted partially to enclose a foot so supported, an X-ray tube revoluble within said cabinet about an axis longitudinally intersecting a foot so supported, a screen revoluble about said foot oppositely to said tube, and means for adjusting said screen parallel to said axis whereby rays traversing different portions of said foot may be received thereby, and means preventing said axial adjustment of said screen except when said screen registers with said rearwardly extending portions of said cabinet.

33. An X-ray machine including a cabinet having a platform adapted to support a foot under load, walls partially enclosing a foot so supported, a narrow panel disposed vertically above the ankle of a foot so supported, and other walls extending rearwardly from said panel and providing upon either side of the patient's limb recesses opening to the interior of said cabinet in combination with a shaft journaled in the front of said cabinet at substantially the level of said platform, a transverse pin extending through said shaft, a fixed bearing sleeve for said shaft provided with a substantially horizontal slot, a bracket carried by said shaft and revolubly and axially movable therewith, an X-ray tube and fluorescent screen supported from said bracket upon opposite sides of a foot supported on said platform, said tube and screen being movable as a unit with said bracket, and a handle on said shaft exterior to said cabinet, said shaft being revoluble to project X-rays on to said screen at a

plurality of angles through said foot, and said shaft being axially movable only when said pin registers with said slot and said tube and screen clear said vertical panel and register with said recesses.

34. An X-ray machine including a cabinet providing a platform adapted to support a patient's foot under load, and a hood partially enclosing a foot so supported and having open portions upon either side of said foot, in combination with an X-ray generating device adjustable rotatably about said foot as a center, and a screen sensitive to X-rays rotatable adjustably about said foot and longitudinally adjustable with reference thereto.

35. An X-ray machine including a cabinet providing a platform adapted to support a patient's foot under load and a hood partial-

ly enclosing a foot so supported, in combination with an X-ray tube, a fluorescent screen, 20 and a bracket in supporting relation to said tube and screen said bracket being mounted for rotation and for axial movement as a unit with said tube and screen.

36. An X-ray machine including a cabinet providing a platform adapted to support a patient's foot under load and a hood extending rearwardly beside a foot so supported, in combination with an X-ray tube adapted to project rays laterally through 30 said foot toward said rearwardly extending hood, and a sensitive screen adjustable longitudinally of said foot within said hood and adapted to receive rays projected through different portions of said foot.

MATTHEW B. ADRIAN.
